UNITED STATES PATENT OFFICE

CARR D. CONDON, OF DES MOINES, IOWA

REFRIGERATING UNIT

Application filed July 2, 1928. Serial No. 289,850.

The object of this invention is to provide an improved portable refrigerating unit for use in refrigerators, ice boxes, refrigerating show cases and the like.

5 A further object of the invention is to provide improved means for maintaining constant low temperatures in refrigerators through the use of a refrigerating unit employing a minimum amount of ice.

10 Still another object of the invention is to provide an improved refrigerating unit which is capable of maintaining low temperatures and dry atmosphere in a refrigerator and which is especially economical in the 15 use of refrigerating agencies.

Still another object is to provide an efficient refrigerating unit which is inexpensive to make and maintain and which is capable of maintaining low temperatures in ordinary 20 refrigerators or refrigerating show cases at a very low expense.

With these and other objects in view my invention consists in the construction, arrangement and combination of the various 25 parts of my device, whereby the objects contemplated are attained, as hereinafter more fully set forth, pointed out in my claims, and illustrated in the accompanying drawings, in which:

30 Figure 1 is a perspective view showing one of my improved refrigerating units in the ice chamber of a household refrigerator.

Figure 2 is a plan view of the refrigerating unit.

35 Figure 3 is a vertical section of the unit on the line 3—3 of Figure 2.

Figure 4 is a horizontal section on the line 4—4 of Figure 3.

40 Figure 5 is a horizontal section on the line 5—5 of Figure 3 and showing particularly, the means for forming ice cubes.

The refrigerating unit formed in accordance with my invention comprises a double-walled container preferably of cylindrical 45 form.

I have employed the numeral 10 to designate the outer wall and the numeral 11 to designate the inner wall which are so arranged and connected as to form a jacket 50 space 12 between them. The jacket space 12

is entirely closed except for a filling opening 13 which is closable by means of a screw plug 14.

The jacket space 12 is adapted to be filled with a heat absorbing liquid or refrigerating 55 fluid such as calcium chloride solution, the solution preferably being between seventy and one hundred degrees.

The major portion of the double-walled container constitutes an ice compartment 15, 60 which is open at its top and closable by a lid 16 provided with a handle 17. The lid 16 is formed with a peripheral flange 18, which fits snugly within the mouth of the chamber 15. The chamber 15 is adapted to be filled 65 periodically with a mixture of cracked ice and salt or sodium chloride, which is designated by the numeral 19.

The refrigerating unit is filled or charged 70 as previously set forth and is placed in the ice chamber such as 20 of a refrigerator or the like 21.

For convenience in handling it, the refrigerating unit is provided with handles 22 on 75 its side walls.

The lid 16 of the container is formed with a plurality of openings 23 preferably arranged in an annular row. A valve plate 24 is mounted on the lower side of the lid 16 and is pivoted thereto by a centrally arranged 80 rivet 25.

The valve plate 24 also is formed with an annular row of openings 26 which are adapted to register at times with the openings 23 of the lid.

The damper plate 24 is provided with an operating knob 27 which extends through an arcuate slot 28 in the lid. By moving the knob 27 in the slot 28 the valve plate 24 may be adjusted to cause the openings 26 to register in whole or in part with the openings 23 or to be positioned so that they are entirely out of registry so that all the openings in the lid are effectively closed.

I have found that by the use of this improved refrigerating unit, charged as previously set forth, I am able to maintain constant and relatively low temperatures in an ordinary ice box or refrigerating show case and that I am enabled to do this with the use 100

of a relatively small amount of ice, namely about one-fifth of the quantity that is usually employed in an ice box or show case of a given capacity.

5 The freezing solution, such as calcium chloride, acts to absorb the heat from the surrounding atmosphere and permits the ice in the unit when contacted by the sodium chloride to act very efficiently as a cooling medium. Not only this, but the surrounding atmosphere is kept in a very dry condition, since all the moisture collects on the outside of the refrigerating unit, as is evident from a heavy accumulation of frost which is visible 10 thereon after the device has been in use for a short time.

By adjusting the valve plate 24 so that the openings 23 of the lid are opened to greater or less extent, I am able to secure even lower 20 temperatures by permitting a circulation of air within the compartment 15 and over the ice and salt mixture therein.

This arrangement of course, causes a faster melting of the ice in the chamber 15, so that 25 a given charge will last for a shorter period of time than when the openings of the lid are closed and a slightly higher temperature is maintained.

However, experiment has amply demonstrated that my improved refrigerating unit 30 is capable of producing and maintaining temperatures considerably lower than can be secured in the same refrigerating devices with the use of ice in large chunks, as ordinarily 35 employed. Experiment has also demonstrated that the temperatures produced by means of this refrigerating unit are kept more constantly at a lower point and are also more effective on account of the atmosphere 40 being dry.

I have also provided means for producing ice cubes through the use of my refrigerating unit and for this purpose, the lower part of the double-walled unit is formed with a recess 29, which is open at its bottom and at one side or end. Within the recess 29 a drawer or the like 30 may be removably 45 mounted, which drawer is provided with partitions 31 to produce relatively small 50 compartments which are filled with water.

When the refrigerating unit is in operation and the drawer 30 is mounted within the recess 29, ice cubes are produced which are useful for household purposes such as for 55 cooling drinking water or which may also be used for other beverages.

My improved refrigerating unit may be constructed principally of galvanized sheet metal or aluminum and is relatively inexpensive, since it employs no machinery and no 60 moving parts.

It is also economical in operation and is effective in a considerable saving of the amount of ice required for a given ice box 65 or refrigerating show case.

In this connection, I might state that for ice boxes or show cases of large capacity, two or more of the refrigerating units may be employed. For instance, in a show case, one of the units may be placed near each end 70 of the show case.

I believe that calcium chloride is the best substance to use for the freezing solution, but it is possible that other substances may be employed with some good results, such for instance as a solution of sodium chloride. 75

It will be noted that this refrigerating unit is entirely self-contained and is not dependent for its successful operation upon connections with other extraneous devices or sources of supply by means of pipes or the like. In other words, the unit is capable of being readily moved from place to place without disturbing its operative condition and it may be placed in any desired location in a refrigerator or show case without the necessity for providing a special location for it. 80

I claim as my invention:

1. A refrigerating unit comprising a double-walled container, whereby a jacket space 90 is provided substantially surrounding an inner compartment, a filling opening for said jacket space, means for tightly closing said filling opening and the jacket space, and a lid 95 for tightly closing the interior compartment, which compartment is capable of being entirely closed to atmospheric air, the jacket space containing a freezing solution and the interior compartment containing a mixture of cracked ice and salt, said unit being entirely self-contained so that it is capable of being transported from place to place and of being readily removed and replaced relative 100 to a refrigerator.

2. A portable, self-contained refrigerating unit comprising a double-walled container, whereby a jacket space is provided substantially surrounding an inner compartment, a filling opening for said jacket space, means for tightly closing said filling opening, and a lid for tightly closing the interior compartment, the jacket space containing a solution of calcium chloride and the interior compartment containing a mixture of cracked ice and salt. 110 115
